UNITED STATES PATENT OFFICE.

JOHN A. GIANNINI, OF PHILADELPHIA, PENNSYLVANIA.

DESIGN FOR A LAMP.

Application filed August 22, 1927. Serial No. 23,179. Term of patent 3½ years.

To all whom it may concern:

Be it known that I, JOHN A. GIANNINI, a citizen of the United States, residing in Philadelphia, county of Philadelphia, State of Pennsylvania, have invented a new, original, and ornamental Design for Lamps, of which the following is a specification, reference being had to the accompanying drawing, which forms part thereof.

The figure is an elevation of a lamp embodying my design.

I claim:

The ornamental design for a lamp as shown. In testimony of which invention, I have hereunto set my hand, at Philadelphia, on this 25 day of September, A. D. 1926.

JOHN A. GIANNINI.
